(57) **CLAIM**

The ornamental design for a motor vehicle, toy replica, and/or other replica, as shown and described.

DESCRIPTION

FIG. 1 is a front elevational view of a motor vehicle, toy replica, and/or other replica showing our new design; FIG. 2 is a rear elevational view thereof; FIG. 3 is a left side elevational view thereof; FIG. 4 is a right side elevational view thereof; FIG. 5 is a top plan view thereof. FIG. 6 is a top, front, and left side perspective view thereof, and, FIG. 7 is a top, rear, and left side perspective view thereof. The claimed design is indicated by the relatively dark portions in the figures. The de-emphasized and relatively light portions form no part of the claimed design.

1 Claim, 7 Drawing Sheets
